UNITED STATES PATENT OFFICE

103,963

DESIGN FOR A BIRD FEEDING STATION

Edward Gay Butler, Boyce, Va.

Application February 11, 1937, Serial No. 67,592

Term of patent 7 years

To all whom it may concern:

Be it known that I, Edward Gay Butler, a citizen of the United States, residing at Boyce, in the county of Clarke and State of Virginia, have invented a new, original, and ornamental Design for Bird Feeding Stations, of which the following is a specification, reference being had to the

accompanying drawing, forming part thereof. The figure is a perspective view of a bird feeding station, showing my new design.

I claim:

The ornamental design for a bird feeding station, as shown.

EDWARD GAY BUTLER.
